UNITED STATES PATENT OFFICE.

GUSTAVE T. JOHNSON, OF CHICAGO, ILLINOIS, ASSIGNOR TO P. B. YATES MACHINE COMPANY, OF BELOIT, WISCONSIN, A CORPORATION OF WISCONSIN.

TURNING-MACHINE.

1,334,305.

Specification of Letters Patent. Patented Mar. 23, 1920.

Application filed May 9, 1919. Serial No. 295,895.

To all whom it may concern:

Be it known that I, GUSTAVE T. JOHNSON, a subject of the King of Sweden, residing at Chicago, in the county of Cook and State of Illinois, have invented certain new and useful Improvements in Turning-Machines, of which the following is a specification.

My invention concerns improvements in turning machines and relates more particularly, but not exclusively, to wood turning machines in which the support for the work or stock is moved toward and from rotating knives, the work being revolved on its own axis at the same time. In such cases it is desirable that the movement of the work support toward and from the cutter knives, especially throughout the field of action of the latter, shall be a right line movement rather than a curved path. It has been proposed heretofore to make the table carrying the revolving work slideable on rollers toward and from the knives, but experience has shown that such construction is not wholly satisfactory because of difficulties in maintaining the parts properly adjusted and because the ways, guides, or bearings for such table are likely to become fouled or clogged with dirt or refuse, and hence the work carriage or table not easily manipulated. It has also been suggested to support the work table or carriage from below on swinging or hinged arms, but in this case the work travels toward the cutters in a materially curved path, whereby if the work is on proper center for one diameter it is off center for all others. Also in this type of appliance if it is desired to turn a piece of stock square the sides of the square will be somewhat concave instead of true plane surfaces.

The prime object of the present invention is to do away with constructions subject to these objections and to provide a parallel-motion link mounting for such work table or stock support which will give the latter a right line motion or plane movement at least throughout the scope or range of action of the revolving knives on the work. Thus the bearings are all rocking bearings which can at all times be kept clean and well lubricated, and which will not become clogged or otherwise interfered with. A further feature of the invention is the provision of means to prevent such mechanism from skewing or twisting out of position. An additional

salient characteristic of the invention is the provision of means to maintain the table carrying the work in substantially upright position throughout the inner range of its movement and to accomplish this result, in the preferred embodiment of the invention, the outer links of the parallel-motion supporting mechanism are made of greater length than the inner link supporting the work table.

In order that those skilled in this art may have a full and complete understanding of the invention and its various advantages both from structural and functional standpoints I have illustrated a preferred and desirable embodiment of the invention in the accompanying drawings forming a part of this specification and throughout the various views of which like reference characters refer to the same parts. It is to be understood, however, that the invention is susceptible of a variety of embodiments varying in many minor mechanical features and that the particular embodiment presented is by way of example only.

In these drawings:

Fig. 1 is a front elevation of the improved machine, the work or wood stock being shown in dotted lines;

Fig. 2 is a plan view of the mechanism shown in Fig. 1;

Fig. 3 is a head end elevation of the appliance with certain parts of the driving mechanism omitted; and

Fig. 4 is a vertical cross-section through the machine.

Referring to the drawings it will be seen that the main-frame 10 is provided with three alined bearings 11, 12 and 13 accommodating a shaft 14 adapted to be rotated by a pulley 15 thereon and equipped with a plurality of suitable cutters or knives 16, 16 of appropriate shape or conformation to produce a product of the desired type or form.

On the two flat horizontal top surfaces 17 of the forwardly-projecting part of the frame, near opposite ends of the machine, I mount two cross-supports 18 and 19 each having at its rear or inner end an apertured extension 20 and at its front end an apertured hood portion 21 open at the bottom and closed at the top. Positioned between these two rear parts 20, 20 and of a length substantially equal to the distance between

- them is a single trussed or braced link 22 hung at its top by appropriate ears 220 on alined threaded pins or shafts 23 mounted in the apertures of sections 20, 20 and provided with nuts 230. The lower part of this link which is of substantial size, at its two ends is pivoted at 24, 24 to the lower inner portion of an upright support or table 25 having a plane or flat top surface.
- 10 Each of the hoods 21 internally receives the upper end of one of a pair of outer or front links 26 hinged thereto on a shaft or pin 27 fitted in bearings of and extended through the side-walls of the hood and projecting down through a registering opening in the top wall of the frame, these two front links at their lower ends being pivoted or hinged at 28 to the front base portion of the support or table 25. It should be noted that the pair of outer or front links 26 are somewhat longer than the single back or inner braced link 22 and the center of shaft 27 is at a slightly higher level than the centers of the supporting pins or shafts 23, this construction being used to give the table 25 a substantially vertical position when it is swung into the field of action of the revolving cutter blades, that is, close to the rear portion of the main frame. As will be readily understood this parallel-motion link mounting for the table gives the upper end of the latter and the work which it carries a substantially-horizontal plane movement toward and from the blades at least throughout their field of action.
- This table 25 has a flat plate 30 hinged to its top face by a bolt 31 and a locking bolt 32 taking through a slot 33 in the plate and threaded into the table, the construction permitting angular adjustment of this plate and the work and its supports with respect to the axis of the cutters or knives.
- At one end such adjustable plate carries a head-stock comprising a bearing 41, a shaft 42 therein, and a work engaging and driving center piece 42^a, the shaft and work being rotated by a sprocket wheel 43 on the former driven by a sprocket or silent chain 44 from a suitable source of power not shown.
- At its other end the table or plate is provided with a tail-stock consisting of a bearing 50, a center shaft 51 reciprocable therein and equipped with rack teeth 58 on its top which are in mesh with those of a pinion 57 on a cross-shaft 54 to which a weighted arm 55 is attached, whereby the weight of the arm holds the center piece up to the work, turning or lifting of the weighted arm retracting the center and freeing the work characterized 56 and shown in dotted lines.
- To provide for adjustment of the tail-stock toward and from the head-stock for the accommodation of pieces of work of different lengths, the top surface of plate 30 is supplied with a pair of parallel longitudinal undercut grooves 60, 60 which receive the heads of the tail-stock holding bolts 61. Obviously, by loosening these bolts the tail-stock may be moved lengthwise the plate and then held firmly in the new adjusted position by tightening the nuts of the bolts.
- In order to shift the work-carrying table toward and from the revolving blades to effect the cutting or turning operation, and to permit the removal and insertion of the pieces of work or stock, the main frame of the machine is supplied at its front with a pair of alined bearings 70, 70 for a shaft 71 provided at its right-hand end with a curved operating handle 72. Fixed to such shaft just inside of its bearings are two arms 73, 73 connected to the table or work support by substantially-horizontal links 74, 74. Obviously, the rocking or oscillation of shaft 71, by its handle or lever, effects a similar movement in the table and the parts which it carries by reason of such link connections.
- The operation of the appliance occurs practically as follows. The cutters 16 revolving in the usual manner, a piece of work is introduced between the centers of the head and tail stocks on the table in the usual manner by manipulation of the weighted arm 55 which retracts the tail-stock center. This introduction of the work is accomplished while the table is forwardly away from the cutters. Thereupon the handle 72 is pushed rearwardly carrying the table and work in the same direction thereby conveying the rotating work or stock into the field of action of the cutters which turn it in the well known way. Upon completion of the turning operation the handle 105 and table are retracted and the turned product removed. It is to be especially noted that the work travels toward the cutters in a straight line the link motion for the table being such that the work throughout the 110 range of action of the knives moves in a horizontal plane as is required with some kinds of turning work and desirable in others. It will be appreciated that by reason of supporting the table by links in the manner shown and described their bearings may be kept clean and free from dirt and the parts maintained in proper adjustment. Furthermore, owing to the difference in length between the links, the table is maintained in a substantially upright position during the turning operation, that is, the table is upright when near the back portion of the frame and is inclined somewhat as the work is carried away from the cutters.
- Many minor mechanical changes may be made in the structure shown and described without departure from the substance and essence of the invention and without the 130

sacrifice of any of its substantial benefits and advantages, and it is to be understood that all such changes falling within the scope of the appended claims will use the 5 principles of the invention.

I claim:

1. In a turning appliance of the character described, the combination of a frame, one or more knives thereon, a support for 10 the work movable toward and from said one or more knives, and a link mounting for said work support constructed to cause the work to travel in a plane throughout the range of action of the knife or knives 15 thereon, substantially as described.

2. In a turning appliance of the character described, the combination of a frame, a revoluble shaft thereon, one or more knives on said shaft, means to rotate said 20 shaft, a support for the work movable toward and from said one or more knives, means to revolve the work, and a link mounting for said work support constructed to cause the work to travel in a plane 25 throughout the range of action of the knife or knives thereon, substantially as described.

3. In a turning appliance of the character described, the combination of a frame, one or more knives thereon, a support for the 30 work movable toward and from said one or more knives, and a link mounting for said work support including an inner link and

one or more longer outer links, substantially as described.

4. In a turning appliance of the character described, the combination of a frame, one or more knives thereon, a support for 35 the work movable toward and from said one or more knives, and inner and outer links pivotally supported at their upper ends 40 on said frame and pivotally connected at their lower ends to said work support, the movement of the work being in a plane throughout the range of cutting action thereon, substantially as described. 45

5. In a turning appliance of the character described, the combination of a frame, a revoluble shaft thereon, one or more knives on said shaft, a support for the work movable toward and from said shaft, means to 50 revolve the work, a link mounting for said support comprising a single braced inner link pivoted to the frame at its upper end and pivoted at its lower end to said work support, and a plurality of longer outer 55 links pivoted at their upper ends to said frame and at their lower ends to said support, said mounting causing the work to travel in a plane toward and from said shaft throughout the range of cutting action 60 thereon, an operating handle, and a connection between said handle and said work support, substantially as described.

GUSTAVE T. JOHNSON.
